Primary Examiner — Rosemary K Tarcza*Assistant Examiner* — Nathaniel D. Buckner(74) *Attorney, Agent, or Firm* — Morgan Lewis & Bockius(57) **CLAIM**

The ornamental design for a dock, as shown and described.

DESCRIPTION

FIG. 1 is a front, right, top perspective view of a dock showing our new design;

FIG. 2 is a front, right, bottom perspective view of the dock shown in FIG. 1;

FIG. 3 is a front elevational view of the dock shown in FIG. 1;

FIG. 4 is a rear elevational view of the dock shown in FIG. 1;

FIG. 5 is a left-side elevational view of the dock shown in FIG. 1;

FIG. 6 is a right-side elevational view of the dock shown in FIG. 1;

FIG. 7 is a top plan view of the dock shown in FIG. 1; and, FIG. 8 is a bottom plan view of the dock shown in FIG. 1. The broken lines immediately adjacent to solid lines represent the bounds of the claimed design and form no part thereof. All other broken lines in the figures depict portions of the dock which form no part of the claimed design.

1 Claim, 8 Drawing Sheets(56)
